FIREPROOF DOOR CONSTRUCTION

Johan Oscar Fugelstad, Stockholm, Sweden

Application June 16, 1949, Serial No. 99,407
In Sweden June 17, 1948

2 Claims. (Cl. 109—65)

1

This invention relates to an improvement in doors for safes and other fire-proof rooms, in which the door as well as the surrounding frame consists of a case-like construction covered at the inside and the outside by metal plates and limited at the sides by transverse portions tightening against each other, said case-like construction being in the ordinary known manner filled with an appropriate insulating material.

In order to obtain a complete insulation between the inner and the outer metal-plate covering it is not only necessary to give the door and the walls a sufficient thickness and to select an insulating material for the space between the covering plates having such properties, that said material, when heated, remains in its position and presents sufficient heat resistance, but the doors and door-frames must also be constructed in such a manner, that the heat will not be led through metallic parts to the inside of the safe or room and that heated air cannot pass through the joint between the door and the frame.

The object of the present invention is to construct the transverse border portions of the door and the door-frame so that the above conditions are fully satisfied.

An embodiment of the invention is shown in the accompanying drawings, in which

Fig. 1 is a transversal section through a door according to the invention in the closed position and

Fig. 2 shows the same door in the opened position.

In the drawing 2 is the door and 1 the door frame, the door being pivotally mounted on pivots 3 in the door frame. In the embodiment herein shown, the transverse portions joining the outer cover plates 4 and the inner cover plates 5 of the door and the door frame, and joining together in the closed position of the door, are divided into three members, joined with interposed insulating sheets by screws or rivets, in such manner that the continuous heat conducting connection between the outer and the inner cover plates are interrupted at least at two places. The transverse portions and the insulating sheets are further arranged so that the borders of the asbestos sheets in the closed position of the door form tightening packings extending around the door. According to the relative movements between the door and the door frame when opening and closing the door, the insulating sheets are disposed with their planes in directions parallel to the tangent to said relative movement. In other words the sheets disposed

along the hinge side of the door are parallel with the plane of the door and the sheets disposed along the other three sides of the door are disposed transversely to the plane of the door.

This is obtained in the following manner. The transverse portions of the hinge-side of the door and the door frame are formed of three gutter-like bars 6, 7 and 8, the outer flanges 6a and 8a of the outer bars 6 and 8 being connected with the corresponding cover plates 4 and 5 respectively. In the example illustrated the flange 6a is connected with the outer cover plate 4 by welding, preferably resistance welding, while the flange 8a and the inner cover plate 5 are separated by an insulating sheet 9 and connected together by screws 10. The flanges of the bars 6, 7 and 8 facing each other are also separated from each other by interposed insulating sheets 11 and connected together by screws 12. The middle portions of the bars are inclined in relation to their flanges so as to form tooth-like extensions 13 engaging between each other and permitting adjacent edge portions of the insulating sheets on the door and the frame to tighten against each other in the closed position of the door.

At the other three sides of the door the transverse portions joining the outer and inner cover plates 4 and 5 with each other comprise two angle bars 14 and 15, one flange of which is connected with the outer or inner cover plate, the other flanges of the two angle bars extending past each other, having an insulating sheet 16 interposed between them and being connected together by means of screws 17. The transverse portions of the corresponding sides of the door frame comprise also two angle bars 18 and 19 connected with the inner and outer cover plates and having their transverse flanges extending past each other, but the distance between said flanges is larger than in the door and have interposed between them an intermediate flat iron bar 22 and insulating sheets 20 and 21 on both sides thereof. The free end of the flange of bar 14 connected with the outer cover plate 4 of the door is bent inwardly to form a lip 24 which in the closed position of the door engages a groove formed between the outer edge of the insulating sheet 21, the transverse flange of the angle bar 18 and a flat iron bar 25 forming part of the transverse portion of the door frame, said flat iron bar 25 extending past the outer edge portion of the insulating sheet 21 and being connected with the angle bar 18 by means of screws 26. The angle bar 19 connected with the inner

cover plate 5 of the frame has its transverse flange extending past the edge of the insulating sheet 20 and forming therewith and with the flat iron bar 22 a groove, which in the closed position of the door is engaged by the edge of a further flat iron bar 27 fixed on the outside of the insulating plate 16, fixed on the angle bar 15 of the door and extending past the edge of said insulating plate, said flat iron bar 27 being connected by screws 28 with the angle bar 15. Gaps are left between the flat iron bar 27 fastened on the outside of the insulating sheet 16 on the door and the transverse flange of the angle bar 14 and between the flat iron bars 22 and 25 fixed on the inside of the insulating sheet 21 on the frame. These gaps, which face each other in the closed position of the door and form a continuous air channel 29 (see Fig. 1) running along the three sides of the door and the door frame. In the closed position of the door the edges of the parts 24 and 27 engaging the grooves in the transverse portion of the frame are pressed against the outward edges of the insulating sheets 21 and 20, the free edges of the parts 19 and 25 engaging the grooves formed between the parts 15 and 27 and the parts 14 and 24. Thereby a combined and multiple labyrinth- and packing tightening is obtained around the whole door between the door and the frame.

As can be seen in Fig. 1 in the closed position of the door the outer and inner cover plates 4 and 5 are in heat conducting connection with each other only through a little number of screws having a relatively little heat conducting cross area which permit only practically unimportant quantities of heat to pass by conduction from the outside to the inside of the door and door frame through their transverse portions.

Any other fastening means than screws, for example rivets, may be used for the connection between the different parts and the number of elements and interposed insulating sheets in the transverse portions of the door and the door frame may be used within the scope of the appended claims.

What I claim is:

1. In a door and door frame construction for safes and other fire-proof enclosures having inner and outer cover plates of metal, transverse border portions joining said cover plates together and forming door jambs and border portions for a door fitting into said jambs, said transverse portions comprising spaced heat conducting sections between the inner and outer cover plates and insulating sheets interposed between said heat conducting sections of said transverse portions, said insulating sheets being fastened between said sections of the transverse portions in positions parallel with the direction of relative motion between the door and the door frame, namely essentially parallel to the cover plates of the door at the hinge side of the door and the door frame and essentially perpendicular to the said cover plates at the opposite side of the door and the door frame, said heat conducting sections of said transverse portions being so profiled and joined together with the insulating sheets, that one edge surface of each of said insulating sheets in at least one of two adjacent transverse portions of the door and the door jamb forms the bottom of a deep groove in which a corresponding projection on the other of said two transverse portions is adapted to engage and to be pressed against said edge surfaces of the insulating

sheets when the door is closed, the insulating sheets of the transverse portions at the hinge side of the door and the door jamb being fastened between plane side flanges of bent metal sheet sections of general U-shaped section, said side flanges being parallel with said insulating sheets and extending inwardly from the transverse portion of the door and the door jamb, the intermediate portions of said bent sections being inclined to said side flanges and adapted to engage grooves formed between two bent sections of the transverse portion that faces the transverse portion of which they form a part.

2. In a door and door frame construction for safes and other fire-proof enclosures having inner and outer cover plates of metal, transverse border portions joining said cover plates together and forming door jambs and border portions for a door fitting into said jambs, said transverse border portions comprising spaced heat conducting sections between the inner and outer cover plates and insulating sheets interposed between said heat conducting sections of said transverse portions, said insulating sheets being fastened between said sections of the transverse portions in positions parallel with the direction of relative motion between the door and the door frame, namely essentially parallel to the cover plates of the door at the hinge side of the door and the door frame and essentially perpendicular to the said cover plates at the other sides of the door and the door frame, said heat conducting sections of said transverse portions being so profiled and joined together with the insulating sheets that one edge surface of each of said insulating sheets in at least one of two adjacent transverse portions of the door and the door jamb forms the bottom of a deep groove in which a corresponding projection on the other of said two transverse portions is adapted to engage and to be pressed against said edge surfaces of the insulating sheets when the door is closed, the insulating sheets of the transverse portions at the hinge side of the door and the door frame being fastened between plane side flanges of bent metal sheet sections of general U-formed section, said side flanges being parallel with said insulating sheets and extending inwardly from the transverse portion of the door and the door jamb, the intermediate portions of said bent sections being inclined to said side flanges and adapted to engage grooves formed between two bent sections of the transverse portion that faces the transverse portion of which they form a part, the insulating sheets of the transverse portion forming the hinge side of the door having one side edge at the bottom of said groove, and the insulating sheets of the transverse portion forming the jamb on the hinge side of the door frame extending outwardly to the pointed angle edge between a side flange and the intermediate portion of the adjacent bent metal section.
